UNITED STATES PATENT OFFICE.

SALVATORE SCOGNAMILLO, OF NEW YORK, N. Y.

RECORD-PUNCHING MACHINE.

1,173,874.

Specification of Letters Patent. Patented Feb. 29, 1916.

Application filed July 10, 1914. Serial No. 850,218.

To all whom it may concern:

Be it known that I, SALVATORE SCOGNAMILLO, a citizen of the United States, residing at New York, in the county of New York and State of New York, have invented new and useful Improvements in Record-Punching Machines, of which the following is a specification.

This invention relates to a sheet perforating machine for producing musical records adapted to be used in connection with mechanical piano or organ players and devices, and the primary object of the invention is to provide a simple organization of electrically controlled elements which positively and automatically operate to accurately or exactly duplicate a preliminarily prepared record in an expeditious manner without requiring any special attention on the part of an operator to effect the result sought, and thereby materially reduce the cost of manufacture of this class of machines and of perforated mechanical records.

The machine embodying the features of the invention has been particularly devised for producing musical records of the perforated sheet type ordinarily rolled upon spools or analogous devices for ready application to a mechanical piano or organ player, but it will be understood that the same mechanism may be used for reproducing any other perforated sheet, such as that used in connection with Jacquard looms and in type machines and the like.

The improved machine embodies a gang or plurality of lever punches which are individually operated or are automatically selected in accordance with the openings in the preliminarily prepared record or pattern by the several mechanisms embodied in the machine.

The machine also involves means for causing the sheet being perforated to move in consonance with or at the same rate of speed as the preliminarily prepared record or pattern, and, furthermore, the variation in the length or size of the openings in the pattern record will be effectively carried out in the reproduction sheet by causing the punch levers automatically selected to operate to have vibrations imparted thereto in order to continuously cut openings in the reproduction sheet exactly corresponding in length to the openings in the pattern record. The invention also consists in the construction and arrangement of the several

parts which will be more fully hereinafter described in preferred form and subject to variations and modifications in the proportions, dimensions and minor details without departing from the scope of the invention as outlined in the appended claims.

In the drawings: Figure 1 is a longitudinal vertical section of a sheet perforating machine embodying the features of the invention. Fig. 2 is a top plan view, broken approximately through the center, and also having portions of the perforating levers removed. Fig. 3 is a transverse vertical section of a portion of the machine taken in the plane of the line 3—3, Fig. 1, and broken through at the center. Fig. 4 is a detail end elevation showing the driving mechanism for one of the rollers or spools and particularly illustrating the ratchet mechanism for checking backward movement or back lash of the spool or roller. Figs. 5 and 6 show detail views, respectively in combined elevation and section, and in cross-section, showing means for holding the end of the paper sheet in separable connection with one of the rollers or spools. Fig. 7 is a detail perspective view of a portion of the cutting means for severing the reproduction sheet from the main body of the sheet after a record has been reproduced or completed. Fig. 8 is a detail sectional elevation of one of the magnets and a portion of one of the punch levers showing the means for breaking the circuit of the magnet to permit the lever to vibrate or oscillate to produce an elongated opening in the pattern record.

The numeral 5 designates a frame which may be of any dimensions and contour and embodies a plurality of parts which will be more particularly hereinafter explained in specifying the application of the various mechanisms and devices thereto, this frame having suitable legs 6 for supporting the same at any desired elevation above a support upon which the machine as a whole may be disposed. At the rear of the frame are uprights or vertical supports 7 that may be suitably tied or braced and having arms 8 projecting forwardly therefrom and continuing into and producing the opposite sides 9 of a bed or table 10 with the opposite ends 11 downwardly curved to permit the reproduction sheet of paper or other material to be readily fed thereonto and therefrom. This bed or table 10 is also provided with upstanding side guides 12 which are

engaged by the side edges of the reproduction sheet to maintain the latter in a positive position relatively to the punching mechanism which will be presently explained. At the front and rear extremities of the bed or table 10, suitably flanged guide rolls 13 and 14 are mounted below the plane of the bed, as shown by Fig. 1, and in suitable bearings 15 of vertical connecting members 16 of the frame under the bed or table 10 a sheet feed roll 17 is mounted and will be provided with any preferred means to prevent the sheet having loose movement relatively thereto, as for instance by the ratchet and pawl mechanism shown by Fig. 4, it being intended to use this ratchet and pawl mechanism wherever desired to check back movement or back lash of any of the rollers. This ratchet and pawl mechanism is well understood in the several arts and it is unnecessary to dwell upon a specific explanation of the same. The bed or table 10 has a transversely extending pocket or channel 18 near the front extremity thereof and depending below the same, said pocket or channel having an outlet opening or slot 19 in its bottom. Within this pocket or channel 18 female dies 20 are mounted and consist of a plurality of steel plates which are less than half the distance between the front and rear walls of the pocket or channel to form vertical openings 21 therebetween, said openings 21 diverging toward and disposed over the lower outlet opening 19. It will be understood, therefore, that each die is composed of two plates 22 which have upper slightly convex edges 23 and are disposed in longitudinal alignment to form a die opening 24, each pair of plates 22 being separated by a steel partition plate 25 extending the full width of the pocket or channel 18 and coöperating with the pairs of plates 22 to complete the several dies 20. The die openings 24 produced by the plates 22 and 25 are preferably of rectangular form, but it will be understood that this shape may be varied at will by correspondingly changing the edges of the dies around the openings. The dies as composed of the pairs of plates 22 and the plates 25 are held in positive positions in the pocket or channel 18 by rods 26 adapted to be suitably secured at their ends in the side portions of the frames and readily removable to take out and repair or replace any of the die members. The plates 25 will also have their upper edges slightly convex so as to accurately coincide with the upper edges of the plates 22, and when all of the die members are assembled and secured in the pocket or channel 18 a continuous convex ridge will be provided in the bed or table 10 over which the sheet, as at S, from the roll 17 is regularly fed, the said sheet also first passing over the guide roller 14 and

then away from the bed or table 10 over the guide roller 13 at the front of the latter.

A fixed fulcrum rod 27 is held between uprights 28 rising from intermediate portions of the arms 8, and on this fulcrum rod an insulating bushing or sleeve 29 is mounted. Punch levers 30 are suspended from the rod 27 and have intermediate apertured enlargements 31 in which the bushing 29 is fitted, there being the same number of levers 30 as there are female dies in the pocket or channel 18; and each lever has a depending punch terminal 32 at its front extremity which is normally held over one of the openings 24 of the dies 20. The levers 30 extend rearwardly from the rod 27 and are preferably provided with upturned rear ends 33 to which springs 34 are attached and also secured to a rod or analogous device 35 extending across and fastened to the uprights 7 at the rear of the frame. The springs 34 tend to draw the rear portions of the levers 30 downwardly and raise the front terminals or punching ends 32 of the levers, and the levers 30 are free to vibrate or oscillate, means being provided to give the levers a vibrating or oscillating movement, as will be hereinafter explained. Each lever 30 also has a rear contact pendant or projection 36 which aligns with a head 37 of a follower or defining lever 38 suspended from a rod 39 secured to the rear portions of the arms 8, an insulating bushing 40 being interposed between the lever head 37 and the rod 39. The head 37 of the lever 38 has an upwardly extending contact projection 41 which rises slightly above the planes of the upper edges of the arms 8 to coöperate with the contact projection 36 of the rear portion of the lever 30 thereover.

There are as many followers or defining levers 38 used as there are levers 30, and the bushing 40 extends fully over the rod 39 and insulates all of the said levers 38. The levers 38 have lower rearwardly projecting contact ends or fingers 42, each lever being provided with a single projection or finger, and engaging each lever 38 also is a spring 43 resting against a fiber or insulating block or strip 44 held by a cross-bar 45 secured to the arms 8. The springs 43 operate to maintain the followers or defining levers 38 in a normally yielding position, but the springs 43 are only of such resilient tension as to insure the performance of contact function and engagement of the fingers 42 with parts disposed for coöperation therewith. The fingers 42 are adapted to engage with metal heads 46 having shanks 47 held between insulating strips 48 secured to horizontal supports 49 extending forwardly from the uprights 7, the shanks 47 projecting rearwardly beyond the insulating strips 48 any suitable distance to receive electrical 130

connections. The heads 46 have front convex edges 50 and unitedly form a guide as well as electrical conductors or contacts for the fingers 42, and over the guide as provided by the heads 46 the pattern record or sheet S' is fed from an upper roller 51 to a lower roller 52, both rollers 51 and 52 being removable from the portion of the frame which they engage.

As shown by Fig. 3, the one arm 8 has a socket 53 with an inner flange 54 and a cross-pin 55, and the other arm is formed with an opening 56 therethrough in alinement with the socket 53 and the outer part of the opening is covered by a cap 57 which is projected by the seat 58, and over the inner part of the opening 56 is a plate or annular disk 59 through which a movable stud 60 extends inwardly, the stud having an outer flanged head 61 engaging a spring 62 held in the opening 56 and seat 58 of the cap 57. The spring 62 forces the stud 60 inwardly and the adjacent head of the roller 51 at the center is provided with a socket 63 to removably receive the stud. The opposite head of the roller 51 has a cylindrical boss 64 with a cross-groove 65 therein to fit over the pin 55. It will be seen that the roller 51 may be readily removed by shifting the roller longitudinally and pressing the stud 60 outwardly until the boss 64 is disengaged from the cross-pin 55, and then the stud 60 may be released from the opposite head of the roller. It will be understood that the bushing 53 with its inner flange 54 rotates in the portion of the arm in which it is mounted, and also that the stud 60 is free to rotate in the annular disk 59 and the opening 56 so that the roller 51 may have a regular rotation imparted thereto. The roller 51 preliminarily carries the pattern sheet or record, and as heretofore indicated, the pattern sheet or record passes over the guide formed by the contact heads 46 and is wound upon the lower roller 52. This lower roller 52 is also engaged and has devices for removing the same similar in all respects to those described in connection with the roller 51 with the exception hereinafter explained, and to the similar parts of the two rollers like reference characters have been applied. Instead of using the bushing 53 as shown in connection with the roller 51, an elongated bushing 65a is provided with the cross-pin 55, the said longer bushing projecting outwardly beyond the lower portion of one of the side members of the frame and having a ratchet wheel 66 screwed or otherwise secured on the outer end thereof and engaged with a pawl 67 secured to the outer face of a bevel gear 68, as shown by Fig. 4, the bevel gear 68 being loose on the bushing 65 and the latter rotated through the operation of the bevel gear 68 through the medium of the ratchet and

pawl just explained. Under the front end of the bed or table 10 is a receiving roller 69 for the reproduced sheet, said roller being in inclined alinement with the guide roller 13 above. The roller 69 is mounted in a removable manner on the frame in precisely the same way as the roller 52 and is provided with a bevel gear 70 similar to the gear 68 of the roller 52. It is obvious that the rollers 52 and 69 must move or rotate at exactly the same rate of speed and the movement of the roller 69 in winding the sheet thereon as reproduced controls the feed of the said sheet over the bed or table 10, and the rate of feed of this sheet over the bed or table must be exactly the same as the rate of movement of the pattern sheet S' as it passes from the roller 51 through the roller 52. To accomplish this uniformity of movement of the rollers 51 and 69 and also the same rate of movement of the sheet S over the bed or table 10 as the movement of the pattern sheet S', a power shaft 71 is provided and mounted in suitable bearings 72 at one side of the machine frame, and on the ends of the shaft 71 are bevel pinions 73 and 74 which respectively mesh with the bevel gears 68 and 70. The bevel pinions 73 and 74 are so positioned relatively to the bevel gears 68 and 70 that the rollers 52 and 69 will rotate in the same direction or have the same winding movement so that the sheet S as reproduced in accordance with the pattern provided in the sheet S' will be coiled on the roller 69 in the same manner as the sheet S' is coiled on the roller 52. On the shaft 71 a sprocket wheel or other analogous device 75 is mounted, and trained thereover is a chain or other belt 76 which extends inwardly and engages a sprocket wheel or similar device 77 on a shaft 78 mounted in suitable bearings 79 and having a friction disk 80 on the end thereof opposite that to which the sprocket wheel 77 is secured. A friction roller 81 is held in continual engagement with the disk 80 and is carried on the inner end of an armature shaft 82 of an electric motor 83, the latter being disposed on a carriage or slide 84 which movably engages a pair of rods 85 extending across the frame and is also provided with an adjusting screw-stem 86 extending outwardly to one side of the frame and provided with a bevel pinion 87 meshing with a similar pinion 88 on the rear end of an adjusting rod or shaft 89 mounted in suitable bearings 90 and having a hand wheel 91 at its front end within easy reaching distance of the operator.

The rod or shaft 89 may be actuated at any time desired to shift the motor 83 and change the point of engagement of the roller 81 with respect to the disk 80 and thus modify the speed of the shaft 78 and the power or drive shaft 71 connected thereto.

as may be found necessary during the reproduction of any pattern. Positively operating means are also provided for severing the reproduced sheet after the latter has been completed in accordance with the pattern to be reproduced, said severing means consisting of a bracket or frame 92, as shown in detail by Fig. 7, embodying a pair of cross-bars 93 with outwardly projecting arms 94 at their ends connected to or continuous with an annular head 95, each pair of arms 94 being provided with a head 95. The bars 93 are spaced apart or separated any suitable distance and likewise the arms 10 94, and the arms are formed with grooves 96 in their inner opposing sides to provide seats for coiled springs 97 which extend outwardly and engage the opposite extremities of a sliding cutter bar 98 preferably formed 15 with an inner beveled cutting edge 99 which coacts with the outer edge of one of the bars 93 in performing its severing function. The cutter bar 98 is actuated by a cam roller or member 100 having trunnions 101 at opposite ends engaging bearings 102 at the outer portions of the heads 95. The cam roller 100 is formed with a cam groove 103 of the contour particularly shown by Fig. 1 and intersecting a shoulder 104 against which the 20 outer portion of the cutter bar 98 has bearing so as to insure a proper rotation of the cam roller 100 in actuating the said cutter bar. The cam roller 100 is operated through the medium of a handle or grip 105 connected thereto, and when the said roller is moved inwardly the reproduction sheet S, which is primarily passed between the outer edges of the bars 93 and the inner beveled edge of the cutter bar 98, is forced against 25 the bars 93 and severed and when the cam roller 100 is released the springs 97 force the cutter bar 98 outwardly and at the same time the roller 100 is rotated in a reverse direction until the cutter bar engages the shoulder 104 when the parts of this cutting mechanism will be in normal position. The cutting mechanism as a whole as just described 30 is secured through the medium of ears or lugs 106 on the ends of the bars 93 to opposite brace members or arms 107 of the frame 35 at a point slightly below the front guide roller 13.

To the upper ends of the uprights 7 above the arms 8 and the punch levers 30 a magnet carrying frame 108 is movably mounted and comprises opposite side bars 109 and a plurality of cross-bars 110, the rear ends of the side bars 109 being fulcrumed or hinged to the upper ends of the uprights 7 and having 40 their front ends detachably secured by screw-bolts or analogous devices 111 inserted therethrough into upstanding supports 112 which are each formed with a socket 113 having a suitable insulation 114 mounted therein. By removing the screw- 45

bolts 111 the frame 108 together with the parts carried thereby may be readily raised and thrown backwardly to give access to the levers 30 below or to permit repair or replacement of any of the devices carried by said frame. The cross-bars 110 have supports 115 secured thereto and projecting from opposite sides at intervals, and these supports have electromagnets 116 suspended therefrom, one magnet from each support. 50 An electromagnet is held over the upper edge of each punch lever 30 and has its pole exposed to the upper edge of its corresponding lever. It will be seen that all of the magnets 116 are arranged in rear of the fulcrum rod 27 of the levers 30, and hence when the rear portion of any one of the levers is drawn upwardly by its magnet the front portion of the same lever will be forced downwardly and the punch extremities 55 32 thereof will be caused to punch the sheet S fed between the said punch extremity and the die beneath.

As more clearly shown by Fig. 8, the core of the magnet is projected as a whole at the upper end of each magnet, and an armature 117 is normally in engagement with the upper end of the core or pole of each magnet and is carried by a pivoted or hinged arm 118 extending from the adjacent portion of the cross-bar 110 which supports the magnet. The core 119 of each magnet is also tubular and has an insulation 120 therein which is likewise tubular, and through the tubular insulation a small rod 121 rises from the upper edge of the adjacent lever 30 and extends upwardly to and engages an insulation 122 on the armature 117. The rod 121 may be secured either to the lever 30 or to the insulation 122, and the latter insulation will extend over only a portion of the armature so as to avoid interfering with the normal metal contact between the armature 117 and the upper end of the core of the magnet. The rod 121 co-operating with each 100 punch lever 30 constitutes a circuit breaker and will break the circuit of the magnet when the lever is drawn upwardly by the lower pole of the magnet, and when the circuit is broken the spring 34 of the lever will 105 immediately draw the lever downwardly and this operation will continue so long as the contact finger 42 of the follower or defining lever 38 of any one of the levers 30 is in engagement with its corresponding 110 contact head 46 and which latter contact is permitted by the openings in the pattern sheet coming over the heads 46 and permitting each finger 42 to pass therethrough and engage its corresponding head. Each lever 115 30 will continue to punch or vibrate so long as its corresponding follower or defining lever 38 has its finger 42 in engagement with its corresponding head 46, and by this means short and longer openings will be formed in 120 130

the reproduction sheet S exactly in accordance with the openings in the pattern sheet S'. When the unperforated portions of the pattern sheet S' move in between the several fingers 42 and the heads 46, the electrical circuit will be broken by reason of the interposition of a non-conducting material between the said fingers and head, and in order to effect an elevation of the rear portions 10 of the levers 30 it will be understood that the magnets 116 will be strong enough to overcome any resisting tendency that may be set up by the contact projections 36 and 41 and also overcome the resistance of the 15 springs 34. Furthermore, care will be taken to so proportion the upper edges of the levers and the poles of their corresponding magnets 116 as to insure that each magnet will influence only the lever with which it is 20 intended to coöperate and thereby avoid magnetic interference and the operation of levers that should not be actuated.

The motor 83 will be supplied with current from any suitable line source, and the 25 magnets will be energized from a battery B held in a suitable inclosure 123 secured to the frame 5. The poles of the battery are connected by wires 124 and 125 to a switch 126' in the manner shown by Fig. 30 1, and all of the shanks 47 are connected by a wire 126' with one of the switch members, the several shanks 47 having short lengths of wire running therefrom to a main wire which will constitute a conductor for all of 35 the shanks collectively relatively to the switch member. The remaining member of the switch 126' is connected by a wire or conductor 127 to the frame 108, and the latter is in turn connected by wires 127^a to the 40 armatures 117, it being understood that these armatures will be suitably insulated from the arms 118 carrying the same. The magnets 116 are also connected by wires 128 and 129 respectively to the levers 30 and the 45 upper ends of the cores 119 of the magnets, the springs 34 being insulated from the levers 30 as shown. As shown by dotted lines in Fig. 1, the magnet carrying frame 50 will be insulated by the interposition of any suitable insulating means at its pivot or hinge connections relatively to the uprights 7 and as indicated at 130.

As shown by Fig. 5, the front or receiving roller 69 will be provided with means 55 for readily attaching the reproduction sheet thereto and for disconnecting said sheet for the purpose of transferring it to another roller. The core of the roller 69 comprises two telescopic tubes 131 and 132 fixed 60 to their respective heads 133 and 134 and extending fully from one head to the other when closed. The tube 131 as shown slides into and out of the tube 132, and each tube has a longitudinal slot 135 and 136 therein 65 which are primarily placed in registration

and the one end of the reproduction sheet inserted therethrough, and then the heads are turned so as to cause the one tube 132 to rotate on the other tube 131 and clamp the paper between the tubes and at the same 70 time partially roll the paper around the core, the rotation of one tube on the other being effected when the tubes are pushed inwardly to a distance approximately equal to the width of the sheet, and when the 75 paper has been thus secured, the roller 69 is then connected to the gear 70 which is arranged in all respects similar to the gear shown in connection with the roller 52, as shown by Fig. 3, and hereinbefore explained. After the sheet reproduced has been completely wound on the core of the roller 69 or subsequent to the severance of the completed reproduced sheet, the heads and tubes of this roller may be readily 80 drawn apart from the opposite ends of the rolled reproduced sheet and the roller again reset in the machine and have the extremity of the sheet S again secured thereto in the same manner for the formation of a further 85 reproduction of the pattern sheet.

It will be understood that a number of the rollers 69 may be supplied with each machine so that no time will be lost in making a substitution of one roller for another that 90 has become filled or has the completed reproduced sheet rolled thereon. It will also be understood that the same form of roller may be adopted at any other point in the machine where found desirable, as for instance the roller 52 may be similarly constructed so as to expedite the detachment of the rolled pattern sheet therefrom. Furthermore, each of the rollers may be provided with means for preventing the sheets 105 from running slack thereon and especially the main feed roller 117, and any of the approved devices for this purpose may be adopted at will. It will also be understood that changes in the proportions, dimensions 110 and minor details may be varied within the scope of the appended claims.

What is claimed is:

1. In a machine of the class described, a plurality of oscillating punch levers and corresponding dies, a pattern sheet, electric circuit making and breaking devices in part carried by the punch levers and between which the pattern sheet has movement, a part of said devices coöperating directly 115 with the levers to make and break the circuit relatively to the levers, the pattern sheet having the openings therein formed in a reproducing sheet which is fed between the punch levers and dies, the two sheets simultaneously moving at the same rate of speed, magnetic means attractively coöperating with portions of the punching levers to effect an oscillation of the latter, and a source of 120 electrical generation connected to a portion 125 130

- of said circuit making and breaking devices and the magnetic means.
2. In a machine of the class described, a plurality of oscillating punch levers and corresponding dies, the levers having contact projections, a pattern sheet, a guide over which the pattern sheet moves and composed of a plurality of conducting heads, a plurality of conducting followers having means 5 for movably engaging the said heads and having direct engagement with said contact projections of the punch levers, the pattern and reproducing sheets respectively having the same rate of movement simultaneously 10 imparted thereto with relation to the pattern guide and the punching levers and dies, and electrical means connected to the said heads and also controlling the oscillation of the punch levers to form the same openings in a 15 reproducing sheet in regular sequence as the openings in the pattern sheet.
3. In a machine of the class described, a plurality of punch levers and dies, the levers having contact projections at their rear portions, a pattern sheet, circuit making and breaking devices between which the pattern sheet has movement, electrically controlled devices in part engaging said contact projections of the levers for oscillating the 20 punch levers, and electrical connections for and between the electrically controlled devices and the circuit making and breaking devices for causing the punch levers to operate to form the same character of openings as embodied in the pattern sheet relatively to a reproduction sheet, the pattern sheet and the reproducing sheet simultaneously moving at the same rate of speed.
4. In a machine of the class described, a plurality of intermediately fulcrumed oscillating punch levers having means attached to their rear extremities for returning them to normal position and also provided with contact projections at their rear extremities, 40 dies corresponding in number to and with which the punch levers coöperate, a movable pattern sheet having perforations, and electrical devices including means normally engaging the contact projections of the levers 45 for automatically operating the said levers to reproduce the perforations of the pattern sheet in another sheet.
5. In a machine of the class described, a plurality of oscillating punch levers having 50 contact projections and corresponding dies, a movable pattern sheet having perforations, magnetic means attractively coöoperating with the upper portions of the levers, a plurality of conducting followers engaging the 55 openings in the pattern sheet and also normally in engagement with the contact projections of the levers, and electrical connections and devices for the magnetic means and for automatically setting up a make and 60 break action relatively to the followers.

6. In a machine of the class described, a plurality of punch levers and corresponding dies, a movable pattern sheet having perforations, and electrical devices including circuit breaking means coöoperating with opposite portions of the levers to operate the latter to exactly reproduce the perforations of the pattern sheet in the same relative position in another sheet.
7. In a machine of the class described, a plurality of oscillating punch levers and corresponding dies, a movable pattern sheet having perforations, electrically controlled devices including circuit making and breaking means above and below and normally 70 engaging the levers and circuits for operating the levers, perforations of the pattern sheet engaging a portion of the electrically controlled devices and by its movement governing the make and break of the electrical 75 circuits to actuate the levers to reproduce the perforations of the pattern sheet in another sheet.
8. In a machine of the class described, a plurality of oscillating punch levers and corresponding dies, electrical devices above and below the levers and embodying circuit making and breaking means for operating the levers, means tending to return the oscillating levers to normal position, and a movable 80 pattern sheet having perforations operating the levers through the electrical devices to reproduce the perforations thereof in another sheet.
9. In a machine of the class described, a plurality of oscillating punch levers and corresponding dies, electrical devices above and below the levers and embodying circuit making and breaking means for operating the levers, means tending to return the oscillating levers to normal position, and a movable 85 pattern sheet having perforations operating the levers through the electrical devices to reproduce the perforations thereof in another sheet.
10. In a machine of the class described, a plurality of oscillating punch levers and corresponding dies, a series of electrical devices including electrical circuits and magnets disposed over portions of the levers and having circuit breaking devices comprising movable means in part engaging the said levers to actuate the latter, and a movable pattern sheet having perforations and engaging a portion of the electrical devices to make and break the magnetic circuit to cause the levers to reproduce the perforations of the pattern sheet in another sheet.
11. In a machine of the class described,

- a plurality of punch levers and corresponding dies, a series of magnets disposed over the levers and having movable members engaging the levers to break the circuits of the magnets, and a movable pattern sheet having perforations and operating to cause the magnets of the levers to be alternately energized and deenergized to reproduce the perforations thereof in another sheet.
- 5 12. In a machine of the class described, a plurality of oscillating punch levers and corresponding dies controlling magnets for the levers having means engaging the latter for breaking the circuits of the magnets, means for returning the levers to normal position, and a movable pattern sheet for alternately energizing and deenergizing the magnets and causing the levers to reproduce the pattern sheet in another sheet.
- 10 13. In a machine of the class described, a plurality of intermediately fulcrumed punch levers and corresponding dies, controlling magnets coöperating with the rear portions of the levers, the magnets having means always in engagement with the levers for breaking the circuits of the magnets by the upward movements of the levers, followers having normal contact with the levers, insulated contact heads coöperating with the followers, and a movable pattern sheet movable between the followers and contact heads and having perforations and operating to alternately energize and deenergize the magnets to cause the levers 25 to reproduce the perforations of the pattern sheet in another sheet.
14. In a machine of the class described, a plurality of punch levers and corresponding dies, controlling magnets having circuit breakers in part engaging the levers, circuit making devices connected to the magnets, and a movable pattern sheet having perforations passing between the circuit making devices and operating to alternately energize and deenergize the magnets to cause the levers to reproduce the perforations of the pattern sheet in another sheet.
- 40 15. In a machine of the class described, a plurality of punch levers and corresponding dies, electrical devices in part coöperating with the levers and including circuits and a source of electrical supply, said devices operating in alternation with respect to opposite portions of the levers to make and break the circuits, and a movable pattern sheet also coöperating with portions of the electrical devices and operating to alternately energize and deenergize a portion of said devices to cause the levers to reproduce 45 the pattern sheet in another sheet.
16. In a machine of the class described, a plurality of punch levers and corresponding dies, a hinged frame mounted over portions of the levers and carrying magnetic devices 55 for operating said levers, said frame and magnetic devices being adapted to be raised and thrown back to clear the levers, make and break electrical devices normally in contact with the lower portions of the levers and controlling the operation of the said 70 magnetic devices, circuits including a source of electrical supply between the electrical devices, and a movable pattern sheet engaging said make and break devices and operating to cause the levers to reproduce 75 the pattern sheet in another sheet.
17. In a machine of the class described, a plurality of punch levers and corresponding dies, a pattern sheet having perforations, a guide over which the pattern sheet moves 80 and composed of a plurality of conducting heads, magnetic devices disposed over and having circuit breaking means coöperating with the levers and connected to the said heads, and a plurality of conducting followers having means for engaging the perforations of the pattern sheet and the said heads, the punch levers and conducting followers having projections which are normally in contact, the perforations of the 85 pattern sheet being formed in a reproducing sheet movable between the levers and dies by the operation of the levers.
18. In a machine of the class described, a plurality of oscillating punch levers and corresponding dies, means for maintaining the punch levers in normal position, a pattern sheet having perforations, magnetic devices disposed over and operating the punch levers, a guide over which the pattern sheet 90 moves and composed of a plurality of conducting heads electrically connected to said magnetic devices, and a plurality of conducting followers normally in contact with the lower portions of the levers and having 95 free extremities for engaging the perforations of the pattern sheet and said heads, the punch levers and conducting followers having projections normally in contact, the perforations of the pattern sheet being formed 100 in a reproducing sheet by the punch levers.
19. In a machine of the class described, a plurality of oscillating punch levers, dies with which said levers coöperate, said dies each comprising two plates having upper 115 slightly convex edges disposed in longitudinal alinement and having an opening formed between their inner edges, and a partition plate extending full width of the said two plates, the partition plates being alternately arranged with relation to each two plates of the die, a pattern sheet having perforations, and means for automatically operating the punch levers relatively to the dies to form the perforations of the 120 pattern sheet in a reproducing sheet.
20. In a machine of the class described, a frame embodying a front table with a transversely extending die pocket therein, a plurality of dies mounted in the said pocket and 125

- comprising pairs of plates with upper convex edges extending only partially across the width of the pocket to provide openings between their inner edges and having partition plates alternately associated therewith, a plurality of punch levers coöperating with the dies, a perforated pattern sheet, and means operated by the perforated pattern sheet to actuate the punch levers to form the perforations of the pattern sheet in a reproducing sheet.
21. In a machine of the class described, a frame having a table, a roll for a reproducing sheet movable over the table, a winding roll for a reproducing sheet, a plurality of punch levers and dies, a pattern sheet having perforations and comprising a carrying roll and a winding roll, mechanism between the winding rolls for the reproducing sheet and the pattern sheet for operating said rolls at a uniform rate of speed, and means for operating the punch levers through the medium of the perforations of the pattern sheet to form perforations in a reproducing sheet corresponding to those of the pattern sheet.
22. In a machine of the class described, a frame having a table, a plurality of dies carried by the table, a plurality of punch levers coöperating with said dies, a pattern sheet having perforations and mounted on a carrying roll, means for operating the punch levers through the medium of the perforations of the pattern sheet to form corresponding perforations in a reproducing sheet, and winding rolls for the pattern sheet and a reproducing sheet each composed of telescopic sections with slots therein adapted to aline to receive the ends of the sheets engaging the same and to be turned to secure and release the said sheets.
23. In a machine of the class described, a frame having a table, punch levers and dies coöperating with the reproducing sheet, a pattern sheet having perforations, means operated by the perforations of the pattern sheet to actuate the punch levers to form perforations in a reproducing sheet corresponding to those of the pattern sheet, and winding rolls for the pattern sheet and a reproducing sheet, each of said rolls having a head and a tubular member with a longitudinal slot therein, the tubular members of the rolls being adapted to telescope and also to rotate with relation to each other for the purpose of securing and releasing the sheets in engagement therewith.
24. In a machine of the class described, a

frame having a table, punch levers and dies coöperating with the said sheet, a winding roll for a sheet adapted to move over the table, said winding roll being removably mounted in the frame and comprising heads and telescopic tubular sections with slots therein, a gear means with which one of the heads is separably associated, and mechanism for operating the said parts including the gear means.

25. In a machine of the class described, a plurality of punch levers and corresponding dies, a pattern sheet having perforations and engaging a carrying and winding roll, means controlled by the pattern sheet for operating the levers, a winding roll for a reproducing sheet, and mechanism for uniformly operating the said winding rolls and embodying a transversely shiftable motor directly operating in connection with the gear means for varying the speed of the winding rolls.

26. In a machine of the class described, a frame having a table, sheet engaging mechanism, a winding roll for a sheet, and a cutting attachment through which a sheet is adapted to move and comprising guides with a cam head rotatably mounted therein and a sliding cutting blade actuated by said head.

27. In a machine of the class described, a frame having a table with sheet engaging mechanism, a winding roll for engagement by a sheet, and a manually operative cutting means located between the winding roll and the front extremity of the table and through which a sheet is adapted to move.

28. In a machine of the class described, a plurality of punch levers and corresponding dies, a table, a pattern sheet engaging a carrying roll, winding rolls for the pattern sheet and for a reproducing sheet, means operative by the pattern sheet for actuating the punch levers, and mechanism engaging the said winding rolls and comprising adjustable gear devices, a motor directly operating with said gear devices, guide means on which the said motor is movably mounted, and a screw-rod and gearing for manually shifting the motor to vary the speed of the winding rolls.

In testimony whereof I have hereunto set my hand in presence of two subscribing witnesses.

SALVATORE SCOGNAMILLO.
